United States Patent Office

Des. 227,050
Patented June 5, 1973

227,050

DISPLAY STAND

James A. Slater, 18A Torrance Road,
Scarborough, Ontario, Canada

Filed Jan. 25, 1971, Ser. No. 109,740

Term of patent 14 years

Int. Cl. D6—04

U.S. Cl. D6—20

FIG. 1 is a side perspective view of the display stand showing my new design;

FIG. 2 is a top plan view of the display stand;

FIG. 3 is a perspective view of one of the display elements.

I claim:

The ornamental design for a display stand, as shown and described.
